AUTOMATIC PROPELLER FEATHERING SYSTEM

Filed May 10, 1949

UNITED STATES PATENT OFFICE

2,601,901

AUTOMATIC PROPELLER FEATHERING SYSTEM

Richard A. Muma, Wichita, Kans., assignor to
Beech Aircraft Corporation, Wichita, Kans., a
corporation of Delaware

Application May 10, 1949, Serial No. 92,355

8 Claims. (Cl. 170—135.29)

1

The invention here disclosed relates to automatic propeller feathering systems of the type covered in the co-pending Wells and Reiter patent application, Serial No. 710,724, filed November 18, 1946, wherein lack of the power required for takeoff, for a predetermined short interval of time at one engine, automatically initiates the propeller feathering operations at that engine.

Special objects of the present invention are to assure feathering operations only of the malfunctioning engine, to make certain the completion of the feathering of the propeller of that engine and to prevent unfeathering operations until so intended by the pilot.

Particularly it is a purpose of the invention to simplify and reduce the number of circuits and parts required.

Further special objects of the invention are to provide the pilot with suitable indication when the system is properly armed and to be relied upon, to give the pilot absolute control at all times for use or non-use of the system and to provide for complete preflight checking of the system.

Other desirable objects attained by the invention are set forth or will appear in the course of the following specification.

The drawing accompanying and forming part of the specification is a diagrammatic illustration of a present preferred embodiment of the invention. Structure and arrangement, however, may be variously modified and changed as regards the immediate illustration, all within the true intent and broad scope of the invention as hereinafter defined and claimed.

The single figure in the drawing is a wiring diagram showing how the various units which go to make up the system may be combined to effect the desired results outlined.

The present system is like that disclosed in the patent application above-identified as involving certain safety or precautionary circuits arranged to exercise supervisory control over the normal feathering circuits as represented by the normal feathering switches 1 and normal feathering relays 2 for each engine.

Thus there is provided at each engine a torque switch 3 for sensing loss of power and a range switch 4 conditioned by throttle and mixture levers 5 and 6 to arm the circuit for the torque switch at a time when maximum power for takeoff is required.

Also, there is provided a timer 7 for permitting initiation of the feathering cycle only if power is absent for a definite limited period of time such

2

as for an interval of one second and a lockin relay 8 for maintaining circuits closed once the feathering cycle has been initiated.

Under the present invention, however, only a single timer and only one lockin relay are required.

This is made possible by the provision of an engine selector relay 9 designed to cut the timer and the lockin relay in on the power failing engine detected and identified by a particular torque switch.

The torque switches 3, of either the mechanical or pressure type, are shown connected at 10 with a battery or other power source 11 and operate each to close in the absence of torque on the engine.

Signal lights 12 suitably placed on the engine panel or elsewhere are connected at 13 to indicate which, if any engine, is lacking in torque.

20 Each torque switch is connected by a line 14 with the range switch 4 for that engine and these range switches are separately connected by lines 15, 16 with magnet windings 17, 18 of the engine selector relay 9 so that closing of either torque switch in the two-engine installation illustrated, with throttle in the full power position and mixture lever set at automatic rich, one or the other of magnet coils 17, 18 will be energized.

The timer 7 is shown as of the electronic type, 30 connected at one side at 19 with the power line 10, and at the opposite side at 20 with circuit closers 21, 22 operated respectively by magnets 17 and 18 of the engine selector relay 9.

Thus, with operation of the torque switch designated for the left hand engine and consequent energization of magnet 17, circuit will be closed at 21 through line 23 leading to magnet 24 of the lockin relay 8 and with energization of magnet 18 for the right hand engine, circuit will be closed at 22 through line 25 to the right hand engine magnet 26 of lockin relay 8.

The delayed action timer 7 prevents the lockin relay from functioning until the torque switch has been closed for a full second or for such other interval of time for which it has been designed.

At the end of the predetermined interval of time, the magnet 24 or 26 of the lockin relay 8 will be energized to close the circuit (magnet 24) through connections 23, 27, armatures 28, 29 and line 30 through the normal feathering relay 2 for the left hand engine, or through lines 25, 31, armatures 32, 33 and line 34 to the normal feathering relay 2 for the right hand engine.

Circuits also will be completed at the same 50 time by the lockin relay 8, in the case of the left

hand engine coil 24, through line 35, armature 36, line 37, armature 38 of lockout relay 39 and line 40 to the normal feathering pressure cutout switch 41; and in the case of right hand engine magnet 26, through connection 42, armature 43, conductor 44 to the second armature 45 of lockout relay and then by way of connection 46 to the normal feathering pressure cutout switch 41.

In each instance the selected magnet 24 or 26 of the lockin relay 8 has a sustaining circuit through the normal feathering pressure cutout switch for that particular engine, which remains closed, supplying power to the normal feathering relay 2 until the feathering cycle is completed, regardless of whether the torque switch continues closed during this feathering period.

This automatic safety feathering can be accomplished in short order, for example, in a total elapsed time of six seconds from moment of loss of torque.

Further, this automatic feathering is operative only in the full power range of the engine, say from approximately three-quarters to full throttle, as determined by the range switch jointly controlled by the throttle and mixture levers covering range of full power throttle settings from sea level to critical altitude for engine over boost.

The delayed action of the timer prevents the automatic circuit from functioning until the torque switch has been closed for a full second or other predetermined period so as not to operate on a momentary loss of power and requiring for operation, a full second of loss, or of torque less than that normally developed in the full power range.

The timer further will not activate the automatic circuit even though the torque switch has been closed for several seconds unless the throttle has been advanced past the three-quarter open position and the mixture control is in the automatic rich position, and then not until a full second after both conditions have been met.

The engine selector relay 9 automatically selects the feathering circuit for the power losing engine, as detected by the torque switch of that particular engine and shown by the engine identifying torque light 12. This relay closes only that one particular feathering circuit and thus makes it impossible to feather more than the propeller of that one non or malfunctioning engine.

The normal feathering pressure cutout switch 41 or 47 opens when full feathered position of the propeller of that circuit is reached. This de-energizes the holding magnet 24 or 26 of the lockin relay 8 to close a circuit of the armature 48 or 49, enabling condenser 50 to discharge through line 51 and armature 48 or 49 and line 52 through the lockout coil 53 of mechanical lockout relay 39 releasing the mechanical lock on armatures 38 and 45 thereby rendering all automatic circuits inoperative.

The charging of the condenser 50 for the above purpose is effected in the illustration during the feathering cycle through connections 19, 54, armature 48 or 49 and connection 51.

When lockout relay 39 is activated as described by the opening of the circuit by the normal feathering cutout switch 41 or 47 at the end of the feathering cycle, all automatic feathering circuits are rendered inoperative and will remain so until the lockout relay is reset.

The lockout relay 39 is reset automatically in the illustration when the propeller is unfeathered

through operation by the pilot of the proper one of the normal feathering switches 1 or by manual operation of a special reset switch indicated at 55 and arranged to close a connection at 56 from the power line 10 through conductor 57 to the reset coil 58 of relay 39.

The automatic resetting is accomplished in the example when the upper or right hand engine feathering switch 1 is operated, by passage of current across contacts at 59 and through conductor 60, the normally closed back contacts 61 of reset switch 55, armature 62 of reset relay 63 and conductor 57 to reset coil 58. In the case of the lower or left hand normal feathering switch 1, the connection of contacts at 64 establishes a circuit through line 65 to reset relay 63 which thereupon shifts armature 62 to contact 66 to run current through line 57 to the reset coil 58.

The automatic feathering circuit lockout relay 39 is mechanically locked closed when the automatic feathering circuit is operative and this eliminates any need for resetting the same each time the aircraft is used.

A reset signal light is shown at 67 connected with the power source through lines 19, 68 and having a contact 69 for engagement by armature 38 when the reset magnet 58 is energized, circuit then being completed through the ground line 49 and normal feathering pressure cutout switch. This reset light thus indicates when the lockout relay is open to ground on the automatic feathering circuit.

To enable the automatic feathering circuits to be tested for each engine prior to takeoff, there is provided in the illustration, a test switch 70, 71 for each engine, connected at 72, 73 to bypass the range switches 4 of the engines. These switches, in conjunction with the single reset switch 55 and reset signal 67, enable the pilot to fully check and put the automatic feathering circuits in condition for operation.

In these tests the pilot may energize an automatic feathering circuit when an engine is running at low torque and stop at will, allowing the engine oil pressure to then unfeather the propeller.

In order that the pilot may have absolute control at all times there is provided in the illustration a master switch 74 in the power line 10, enabling the pilot to instantly stop automatic feathering on an engine resuming power and whereupon it will unfeather the propeller by engine oil pressure. The circuit lockout relay 39 must then be reset by reset switch 55 to restore the automatic feathering circuit. Also, if the propeller blades are moved from the feathered to an unfeathered position by hand, after being feathered by the automatic circuit, the automatic circuit lockout relay must be reset by means of the reset switch 55 or the normal feathering switch 1.

The master switch 74 ordinarily may be closed only during takeoff.

The system is so designed that the propellers will not feather under standard procedure for engine shut-down or under sudden increase of power on landing approach or emergency power to clear landing field, providing engines exceed wind milling R. P. M., usually approximately 1100 R. P. M., one second after throttle lever has reached full power range, or high altitude flying with throttles in full power position and mixture set at automatic lean.

Servomotors for actuating trim tabs and cor-

recting throttle settings to trim the airplane about yaw axis are indicated at 75, 76, connected respectively by lines 77, 78, with contacts 79, 80, of the lock-in relay magnets 24 and 26, engageable by the armatures 29 and 33.

The selector relay, through the agency of the lock-in relay, selects the proper servomotor to compensate for loss of power of the failing engine. Return of trim under power conditions may be accomplished through use of the normal feathering switch.

While shown applied to a two engine installation, it will be appreciated that the invention is applicable to four, six or other engine airplanes.

The system is of compact, simple design, readily applicable to existing aircraft and provides automatic safety control, in addition to absolute or arbitrary control by the pilot.

The test switch circuits enable the pilot to make certain that the automatic safety circuits are in operative condition, ready for flight, and this together with the absolute control afforded by the master switch 74, provides a sense of security and reliability, enabling the pilot to use the system with confidence and to the fullest possible safety advantages.

Operation

For normal takeoff the feathering master switch 74 is closed, as indicated in dotted lines. This arms the entire feathering system, both normal and automatic.

When ready for takeoff the mixture control levers 6 are placed in auto-rich position and throttle levers 5 advanced to full power range, closing range switches 4, as shown by the dotted lines.

Assuming failure of the right-hand engine during takeoff under full power range, the condition of parts will be as indicated in the broken lines, as follows:

The right-hand engine torque switch 3 closes, energizing coil 18 of selector relay 9 through connection 14, the right-hand range switch 4, wire 16, coil 18, wire 81 and to ground by armature 82 of the deenergized selector relay coil 17.

Coil 18 closes a circuit at armature 83 from the power line 10 through connection 84 to the timer 7.

Coil 18 also closes circuit between the timer relay 85 and magnet coil 26 of lock-in relay 8, by way of conductor 20, armature 22 and conductor 25. At such time also armature 86 of coil 18 opens the ground circuit for coil 17 of this relay.

If the right-hand torque switch remains closed for the preselected length of time determined by timer 7, say approximately one second, the timer relay 85 will close circuit from the battery to lock-in relay coil 26 through line 19, timer relay 85, line 20, armature 22, line 25, coil 26 and to ground through line 42, armature 43 of deenergized lock-in relay coil 24, line 44, armature 45 of lock-out relay 39 and by way of line 46 through the closed contacts 87 of right-hand test switch 71 to right-hand engine normal feathering pressure switch 47.

The energized coil 26 of lock-in relay 8 connects power line 10 to condenser 50 through connections 19, 54, armature 49 and connection 51.

At the same time servomotor 76 is energized through lines 19, 54, armature 33, contact 80 and line 78.

The normal feathering relay 2 for the right-hand engine is energized at this time through 75

lines 19, 54, armature 33 and line 34 to close the right-hand feathering motor switch 88, initiating propeller feathering operation.

The lock-in relay coil 26 also disconnects the grounding connection for the other relay coil 24, at armature 36, thus preventing coil 24 from being energized during such operations.

Coil 26 of lock-in relay 8 becomes self-energized by closing of armature 32, which then completes circuit from lines 19, 54, through lines 31 and 25 to coil 26 and to ground through the normal feathering pressure switch 47 through connections 42, 43, 44, 45 and 46.

With coil 26 self-energized as described, circuits are held closed until the feathering cycle is completed. When the propeller becomes fully feathered the normal feathering pressure switch 47 disconnects the circuit to ground and coil 26 is deenergized, opening circuits at armatures 49, 33, 32, and closing grounding circuit at armature 36 for the other coil 24.

With the battery or power circuit broken as described, condenser 50 which has been charged during the feathering cycle, discharges through line 51, armature 48 of coil 24 and line 52 through trip coil 53 of the lock-out relay 39, releasing and opening armatures 45 and 38 of the lock-out relay, disconnecting circuit 46 to right-hand normal feathering pressure cutout switch 47 and connecting the reset light 67 in circuit.

Further feathering is then impossible until the system is rearmed through the reset switch 55, because the lock-out relay 39 controls both right-hand and left-hand engine feathering systems. Reset switch 55 can be operated as above described to close circuit at 56, thus to energize the reset coil 58 of lock-out relay 39 through connections 57.

The sequence of operation of the left-hand feathering system is similar to the sequence of operation for the right-hand engine, as described.

Test switches, 70 for the left-hand engine and 71 for the right-hand engine, serve as by-passes for the respective range switches 4, enabling the pilot to test the circuits for either side at any time.

In the system here disclosed the mixture control and throttle levers must be operated in this particular sequence to arm the safety feathering circuits. This requirement avoids arming the circuits unnecessarily as at times when automatic feathering would not be required and would not be in order.

What is claimed is:

1. An automatic safety feathering system for multi-engine aircraft having normal propeller feathering circuits for the engines and comprising torque switches subject to engine torque and means connecting said torque switches with said feathering circuits, including a timer for initiating delayed action of the feathering circuits and engine selector relay means controlled by torque switches of the individual engines for selectively connecting said timer with the feathering circuits of the different individual engines.

2. An automatic feathering system for multi-engine aircraft comprising propeller feathering means for each engine, an automatic torque switch for each engine, a timer for instituting delayed action of said propeller feathering means and an engine selector controlled by said torque switches for selectively connecting said timer with the propeller feathering means of different individual engines.

3. An automatic safety feathering system for aircraft having a plurality of engines and comprising in combination with propeller feathering means and power loss sensing means for each engine, a delayed action timer and selector means controlled by the individual engine power loss sensing means for automatically connecting said delayed action timer with the propeller feathering means of a power losing engine detected by said power loss sensing means.

4. An automatic safety propeller feathering system comprising in combination with the normal feathering systems of the individual engines of a plural engine installation, a torque switch for each engine, lockin relay means for maintaining said feathering systems operative throughout a predetermined feathering cycle, selector relay means controlled by said torque switches for automatically connecting said lockin relay means with the normal feathering system of a torque losing engine detected by one of said torque switches, a timer for delaying operation of said normal propeller feathering systems for a predetermined interval of time and means controlled by said selector relay means for connecting said timer with said lockin relay means.

5. An automatic safety propeller feathering system comprising in combination with the normal feathering systems of the individual engines of a plural engine installation, a torque switch for each engine, lockin relay means for maintaining said feathering systems operative throughout a predetermined feathering cycle, selector relay means controlled by said torque switches for automatically connecting said lockin relay means with the normal feathering system of a torque losing engine detected by one of said torque switches, a lockout relay for rendering said lockin relay inoperative at the end of the predetermined feathering cycle and a reset switch for releasing said lockout relay to restore the lockin relay means to operative condition.

6. An automatic safety propeller feathering system comprising in combination with the normal feathering systems of the individual engines of a plural engine installation, a torque switch for each engine, lockin relay means for maintaining said feathering systems operative throughout a predetermined feathering cycle, selector relay means controlled by said torque switches for automatically connecting said lockin relay means with the normal feathering system of a torque losing engine detected by one of said torque switches, a lockout relay for rendering said lockin relay inoperative at the end of the 55

predetermined feathering cycle, a reset switch for releasing said lockout relay to restore the lockin relay means to operative condition and a reset signal associated with said lockout relay.

5 7. An automatic safety propeller feathering system comprising in combination with the normal feathering systems of the individual engines of a plural engine installation, a torque switch for each engine, lock-in relay means for maintaining said feathering systems operative throughout a predetermined feathering cycle, selector relay means controlled by said torque switches for automatically connecting said lock-in relay means with the normal feathering system of a torque losing engine detected by one of said switches, a lock-out relay for rendering said lock-in relay means inoperative at the end of the predetermined feathering cycle and means for tripping said lock-out relay at the end of the predetermined feathering cycle.

10 8. An automatic safety propeller feathering system comprising in combination with the normal feathering systems of the individual engines of a plural engine installation, a torque switch for each engine, lock-in relay means for maintaining said feathering systems operative throughout a predetermined feathering cycle, selector relay means controlled by said torque switches for automatically connecting said lock-in relay means with the normal feathering system of a torque losing engine detected by one of said switches, a lock-out relay for rendering said lock-in relay means inoperative at the end of the predetermined feathering cycle and means for tripping said lock-out relay at the end of the predetermined feathering cycle, including a condenser connected to be charged during the feathering cycle and a relay trip coil connected and arranged to be energized by discharge of said 40 condenser at the end of the feathering cycle.
